UNITED STATES PATENT OFFICE.

WILLIAM A. KIMBELL, OF BIRMINGHAM, ALABAMA.

PLOW.

1,158,134.

Specification of Letters Patent.

Patented Oct. 26, 1915.

Application filed January 23, 1915. Serial No. 3,959.

To all whom it may concern:

Be it known that I, WILLIAM A. KIMBELL, a citizen of the United States of America, residing at Birmingham, in the county of 5 Jefferson and State of Alabama, have invented certain new and useful Improvements in Plows, of which the following is a specification.

My invention relates to improvements in 10 plows and particularly the design of the plow standard and the manner of attachment of the plow point to the standard.

One object of my invention is to form the 15 standard by a single thickness of a metal bar, the upper end of which is seated in a slot in the bottom of the beam and adjustably mounted therein in the manner which forms the subject matter of a divisional application and which is not claimed as a 20 part of this particular invention.

A further novel feature of my invention resides in the design of the clip which is 25 adjustably attached to the foot of the standard and serves to supplement its width so as to give a sufficient bearing for the plow point on one side and, if desired, for the heel scrape on the other side, and at the same time to avoid increasing the draft of the plow by offering any obstruction to the 30 ground.

My invention further comprises the novel details of construction and arrangements of parts which in their preferred embodiments are hereinafter more particularly described 35 and illustrated in the accompanying drawings which form a part of this specification, and in which:—

Figure 1 is a side elevation of the plow complete with the beam partly broken 40 away. Fig. 2 is an enlarged detail view of the plow point attaching means taken on the line $x-x$ of Fig. 1. Fig. 3 is a detail view similar to Fig. 2 showing the clip more 45 in detail. Figs. 4 and 5 are sectional views taken on the lines $y-y$ and $z-z$, respectively, of Fig. 1.

Similar reference numerals refer to similar parts throughout the drawings.

In the preferred embodiment of my invention which is illustrated in the drawings 50 the plow is shown provided with a wooden beam 1 having handles 2 of usual construction, the beam having in its underface a vertical longitudinally disposed slot extending part way up through the beam from near the handles to a point substantially

midway of the beam where the slot extends vertically upward, if desired, passing through the top of the beam. The slot is made just wide enough to receive the standard 4 which is formed preferably of a single bent metal bar having at its forward end an upturned curved lug 5 in which I provide a series of bolt holes 6. The upper portion of the standard which fits in the slot 3 I have 60 designated by the numeral 7 and this portion is of substantial length and is pivotally connected at its rear end to the beam by a cross bolt 8 disposed near the rear end of the slot 3. The rear vertical edge of the lug 70 5 and the series of bolt holes 6 are both struck on curved lines from bolt 8 as a center and the rear wall 9 of the vertical extension of the slot 3 is struck on a similar curve. A bolt 10 is passed through the beam and 75 through one of the bolt holes 6 to attach the forward end of the standard to the beam adjustably so that the plow point 11 may be set at the desired angle. It will be noted that the standard 4, where it drops below 80 the beam 1, is of single thickness and is brought forward on a gradual curve and that the front edge 12 thereof, from the beam down almost to the point of attachment to the plow point, is sharpened to reduce its resistance to the earth to a minimum.

The lower forward edge of the standard is provided with a pair of notches 13, either 85 of which is adapted to receive a clip. This 90 clip, as seen in Figs. 2 and 3, is provided with a side member 14, a bottom member 15 which extends at right angles to 14 and is provided at its outer end with an upturned 95 lip 16, and a top member 17 which is bent downwardly at an intermediate point so as to bring its outer end 18 into parallelism with the member 15 and spaced therefrom with the width of the standard 4 where it is notched. I provide an upturned lip 16 on the outer end of the member 18. The top 100 and bottom members 15 and 17 of the clip near the side member 14 are spaced the full width of the standard and are provided with alining bolt holes 19, see Fig. 3, which are 105 spaced sufficiently from the lipped ends of said arms to permit a strong heavy bolt 20 being inserted and to fit snugly between the side 14 and the standard 4 when the latter 110 is inserted between the top and bottom walls of the clip and hold the standard against the lips 16. Any suitable style of plow

point 11 may be attached by means of the bolt 20 to the standard and a heel scrape 21 may be likewise attached to the rear end of the bolt.

5 In practice, the clip 14 is engaged in either of the notches 13, according to the elevation at which it is desired to attach the point and scrape, this being accomplished, as shown in Fig. 3, by engaging the lower member 15 under the standard and passing the upper lip through and beyond the notch. The clip is then tilted to bring its side 14 into parallelism with the side of the standard and is then drawn outwardly until the 10 lips 16 engage the far side of the standard 4, leaving just space enough between it and the side 14 of the clip for the bolt 20 to be driven down between the two. It will be noted that the part 17 of the upper clip member stands flush with the forward edge of the standard 4 when the parts are in this position and thus presents a substantial bearing face for the plow point. The insertion of the bolt between the clip and the 15 standard attaches the parts together substantially as if they were an integral structure and at the same time it presents the least possible obstruction in cutting the ground. The objects of my invention will 20 be accomplished if the clip is designed at its end to embrace the standard and to receive between its body portion and the standard the blade retaining bolt which passes through the ends of the clip and the blade, 25 and various constructions having this principle may be designed without departing from my invention.

Having thus described my invention, what I claim as new and desire to secure by Letters Patent, is:—

40 1. In combination, a plow standard formed of a metal bar of single thickness, a clip adapted to embrace the standard, a blade, and a retaining bolt which passes through the blade and through both ends of the clip and is projected to one side of the standard to mount the several parts thereon, substantially as described.

2. In combination, a plow standard 50 formed of a metal bar of single thickness, a clip adapted to embrace the standard, a blade, a rearward sweep, and a retaining bolt which passes through both ends of the clip and through the blade and rearward sweep 55 and is projected to one side of the standard, as and for the purposes described.

3. In a plow, a standard formed of a bar 60 having a notch, a clip having a side and top and bottom members, said latter members having inturned lips at their outer ends, said lips being spaced to pass only when the clip

is cocked over a notched part of the bar and being adapted when the clip is righted to engage a side of the bar, a bolt adapted to be passed between the bar and side of the 65 clip to hold the latter interlocked with the bar, and one or more tools adapted to be attached to the standard by said bolt and to bear against the clip and the standard, substantially as described.

70 4. In a plow, a beam, a standard connected to the beam and formed of a bent metal bar of single thickness which is notched near its lower edge, a clip adapted to be interlocked with the standard opposite a notch therein 75 and having a portion standing flush with the forward unnotched edge of the standard and a portion which engages in said notch, a plow point bearing on the clip and the standard, and a bolt for attaching the point 80 adapted to be passed through the ends of the clip and between it and the standard to lock the parts in assembled position.

5. The combination with a plow standard having a notch in its lower forward edge, of 85 a bent metal clip comprising a side member and top and bottom members set at right angles thereto, said top member having its outer end bent inwardly approximately the depth of the notch in the standard, the outer 90 end of the top and bottom members being inturned and adapted to clasp the standard between them when the top member is seated in a notch, there being openings in the top and bottom members to receive a bolt which, 95 in passing between the side member and the standard, is adapted to lock the clip and standard rigidly together.

6. In combination, a plow standard formed 100 of a bent metal bar of single thickness, said bar having a plurality of spaced notches in its lower forward edge, a metal clip comprising a side member and end members bent at right angles to the side member and spaced the width of the standard and having 105 their outer ends provided with inturned lips, the outer part of one end member being bent inwardly the depth of the notch in the standard, said clip being adapted to interlock with a notched portion of the standard to form a bearing for a plow and having bolt openings in its end members, and a plow attaching bolt which is adapted to be passed through the clip ends and between the side of the clip and the standard to hold the clip 110 and standard interlocked.

115 In testimony whereof I affix my signature in presence of two witnesses.

WILLIAM A. KIMBELL.
